(57) **CLAIM**

We claim the ornamental design for the cable connector hood, as shown and described.

DESCRIPTION

FIG. 1 is a top, left, rear, isometric view of a cable connector hood;

FIG. 2 is a left side elevational view thereof, the right side elevational view being a mirror image of the left side elevational view;

FIG. 3 is a top planar view thereof, the bottom planar view being a mirror image of the top planar view;

FIG. 4 is a front elevational view thereof; and,

FIG. 5 is a rear elevational view thereof.

The broken lines are for illustrative purposes only and form no part of the claimed design.
